R. RANDALL.
FRUIT PICKER'S RECEPTACLE,
APPLICATION FILED OCT. 16, 1914.

1,152,217.

Patented Aug. 31, 1915.

UNITED STATES PATENT OFFICE.

REUBEN RANDALL, OF VERNON, BRITISH COLUMBIA, CANADA.

FRUIT-PICKER'S RECEPTACLE.

1,152,217.

Specification of Letters Patent. Patented Aug. 31, 1915.

Application filed October 16, 1914. Serial No. 867,081.

To all whom it may concern:

Be it known that I, REUBEN RANDALL, residing at Vernon, British Columbia, Canada, (present address Summerland, British Columbia,) a citizen of Canada, have invented certain new and useful Improvements in Fruit-Pickers' Receptacles, of which the following is a specification.

This invention embodies improvements in buckets of the type especially adapted to be carried by fruit pickers and suspended ordinarily from the shoulders of the operator by straps or similar means, leaving the hands of the fruit picker free to facilitate the picking operation.

The particular object of the invention has been to device a bucket of the above mentioned kind wherein a flexible bottom spout is provided, same being adapted to be gathered into closed condition so as to provide a closure at the bottom of the bucket, mere releasing of the said gathering means, however, permitting the contents of the receptacle to flow out of the same into a bag, barrel, or like container.

Another object of the invention has been to provide a specially arranged gathering cord or rope for said flexible spout guided peculiarly through stationary and movable guide members carried by the bucket or receptacle, this feature together with other details of the invention being more fully explained hereinafter in connection with the accompanying drawings, wherein:—

Figure 1 is an elevation of a fruit picker's bucket embodying the invention, the bottom spout being shown closed in full lines and open in dotted lines and the lower portion of the bucket being broken away to bring out the fastening means by which the flexible spout or member is attached to the bucket body. Fig. 2 is an end view of the same, the supporting shoulder straps being broken away. Fig. 3 is a top plan view of the bucket, the suspending straps omitted.

In the drawings the bucket is illustrated as comprising the body A made of metal and elongated in cross section, see Fig. 3, one of the side walls of the bucket being curved outwardly as at *a* while the opposite side of the wall is correspondingly curved inward as at *b*, the latter curvature being designed to adapt the bucket to fit against the body of the fruit picker from whom the receptacle may be suspended.

Suitably connected with the upper portion

of the body A are the suspension straps 1 attached by snap hooks to the receptacle and suitably adjusted by buckle means or the like.

The bottom of the receptacle A constitutes a flexible spout B, same being made of fabric material of a suitable nature joined with the lower end of the receptacle A by means of a clamping ring or similar member 2. 60 A gathering rope 3 is connected with the open or lower end of the spout B by means of rings 4 and the action of said rope to lift and tightly close the member B is quite evident upon reference to the several figures 65 of the drawing. After being threaded through the rings 4 on the flexible spout or bottom member B the gathering rope 3 passes through a relatively stationary guide member consisting of a pivoted loop 5 directly attached to the upper portion of the part B. From thence the rope 3 passes through a movable or suspended guide loop 6, the latter being carried by a short chain or flexible device 7 directly attached to the 70 upper portion of the receptacle body A. In the operation of closing the bottom spout B it is merely necessary to pull the gathering rope 3 so that the latter will be pulled taut through the members 5 and 6, after 75 which the free end portion or portions of the rope 3 will be engaged with a spring clip 8 attached to the end of the receptacle. Under these conditions the bottom of the bucket will be maintained closed. After the 80 bucket is filled, by disengaging the rope 3 from the clip 8 and slackening on the same, the weight of the fruit in the bucket will spread the spout B into open condition, permitting the contents of the receptacle to flow 85 into a barrel, bag, or other container as desired.

The employment of the guide members 5 and 6 is advantageous in that the member 5 guides the rope 3 in such a way as to always 100 pull the flexible bottom member B into the same position, namely at the inwardly curved side *b* of the receptacle body A. The member 6 is utilized as a guide and supporting means for the rope located at a 105 point near the end of the receptacle and at a place not intermediate the bucket body A and the body of the person carrying said bucket. Owing to the fact that the member 6 is loosely suspended, it is obvious that 110 the same may be raised or lowered in order to adjust the point of guiding support for

the rope 3 correspondingly, this depending somewhat upon the size and the form of the person who carries the bucket, whereby the invention may be most conveniently supported on the person.

Having thus described the invention, what is claimed as new is:—

A fruit picker's bucket consisting of a rigid metallic body of elongated form in cross section having one side curved outward and the other correspondingly curved inward, a flexible bottom spout attached to said body, a gathering cord connected with the free end of the said spout whereby to close or open the same at will, a guide loop located at the lower end of the bucket adjacent to the inwardly curved side of the

latter and having the gathering rope passing therethrough, a clip secured to one end of the body and arranged to engage with the gathering rope, a flexibly suspended guide loop suspended from the upper end of the body at its inwardly curved side and located intermediate the first mentioned guide loop and the clip, the gathering rope passing through said suspended loop, and suspension means for the body for attaching the bucket to the person.

In testimony whereof I affix my signature in presence of two witnesses.

REUBEN RANDALL.

Witnesses:

D. R. WHITE,
